DESIGN FOR A COOKING RANGE

Carl Reynolds, Jr., Detroit, Mich., assignor to
Moffats Limited, Weston, Ontario, Canada, a
corporation

Application June 12, 1948, Serial No. 146,921
In Canada May 27, 1948

Term of patent 14 years

(Cl. D81—4)

To all whom it may concern:

Be it known that I, Carl Reynolds, Jr., a citizen of the United States, residing at Detroit, in the county of Wayne and State of Michigan, have invented a new, original, and ornamental Design for Cooking Range, of which the following is a specification, reference being had to the accompanying drawing, forming part thereof.

Fig. 1 is a perspective view of a cooking range, showing my new design, and showing particularly the top, the front, and one side thereof; and

Fig. 2 is a top plan view thereof.

The side of the range not illustrated in the drawings is identical to the side shown, whereas the rear wall thereof is plain.

I claim:

The ornamental design for a cooking range, as shown and described.

CARL REYNOLDS, JR.
